INTRA-ABDOMINAL RETRCTOR

Ralph W. Homer, Ventura, Calif.

Application June 14, 1932. Serial No. 617,147

9 Claims. (Cl. 128—20)

This invention relates to surgical appliances and particularly to retractors for maintaining the walls of cavities or various organs of the body out of the way during an examination or operation.

An object of the invention is to provide means insertable within a body cavity for retracting organs or tissues away from a particular spot to be examined or operated upon.

10 In the drawing:

Figure 1 is a sketch illustrating in a general way how an appliance in accordance with the invention is inserted through an abdominal incision and expanded into a desired position;

15 Figures 2, 3, and 4 are plan views illustrating various shapes in which a device in accordance with the invention may be constructed; and

Figure 5 is a cross sectional view showing the construction of the device illustrated in Figures 20 2, 3, and 4.

In operating on various organs within the abdominal cavity it is common practice to enter the abdomen through an incision in the belly of the patient; this incision, which is in the form 25 of a slit, is kept open by retractors of conventional form which hook over the edges of the incision and spread them apart. However the abdominal cavity is filled with a mass of organs, many of which are more or less loosely attached 30 to the walls of the cavity, and which tend to crowd together. It is therefore usually necessary for a surgeon to separate or press to one side the mass of viscera in order to obtain access to a desired organ. In many instances it is 35 necessary to have an assistant at an operation whose sole duty is to hold the visceral mass out of the way with his hands. Obviously, such an assistant is in the way; furthermore, his duties are fatiguing and it may be difficult for him to 40 maintain the viscera in a desired position for a long period of time. In some instances it is impossible to utilize an assistant, and the surgeon must himself maintain the bulging mass of 45 tissues and viscera out of the way while he operates.

In accordance with the present invention there is provided a flexible plate which can be made in various shapes and sizes and can be shaped within the body cavity to form a dam for retaining the obstructing viscera out of the way of the surgeon. The essential characteristics of this plate are that it have a smooth non-porous surface of an insoluble, non-poisonous material capable of being sterilized, and that it be non- 50 elastic and sufficiently rigid to retain any shape

into which it may be bent, against the pressure of the tissues or organs it is to retract; at the same time being sufficiently pliable to be easily bent with the hands.

A very satisfactory plate satisfying the above 60 requirements comprises a core of thin sheet lead enclosed in an envelope of soft rubber. As shown in the cross sectional view of Figure 5, such a plate may be constructed by sandwiching a sheet of lead 2 between two sheets of rubber 65 of slightly larger dimensions, and vulcanizing the three sheets into a single integral unit in which the lead core is completely enclosed by the rubber. The soft rubber walls extend out a short 70 distance beyond the edges of the lead core as shown at 8 to serve as cushions and prevent injuries to tissues with which they come in contact. Plates as described may be constructed in a variety of shapes and sizes to serve different 75 purposes. Three possible shapes are shown in Figures 2, 3, and 4 respectively and the dimensions of each of these plates may be varied to satisfy different requirements.

In many cases the plate desirable for a particular 80 purpose will be too long to be readily inserted through an incision. In such instances, as shown in Figure 1, the plate may be coiled into a roll as indicated at 3, for insertion through the incision; the retracted edges of the incision are indicated at 4. After insertion within the abdominal cavity the plate may be uncoiled to form 85 a dam in a desired position and of a desired shape as indicated by dotted lines at 5. Even though the initial coiling or rolling of the plate be unnecessary to enter it through the incision, such preliminary coiling is often desirable as the compact roll may be readily inserted between crowded organs; then as the roll is expanded by the 90 surgeon, the organs are pushed away from the spot 95 desired to be cleared and maintained in the position to which they are pushed.

A retractor having a lead core is very satisfactory for the reason that lead is extremely pliable and may be bent repeatedly into many shapes 100 without breaking; it is also substantially non-elastic and remains in any shape to which it may be bent. The hermetically sealed envelope of rubber prevents any contact of the lead with the body tissues.

A retractor shaped as shown in Figure 2 is 105 particularly useful where it is desired to form a dam within the abdomen extending transversely across the body. The curved lower edge 6 of the retractor then fits across the back bone of 110

the patient and the lobes 7 fill the depressions on either side of the back bone.

A retractor of the shape shown in Figure 3 is useful where a high retracting wall is necessary on only one side, and a low wall suffices at other points. The low wall may be advantageous in that it is less in the way of the surgeon.

Although many special uses of the retractor will be apparent to surgeons, it is particularly useful in prostate gland operations in which access to the gland is obtained by penetrating both the anterior and posterior walls of the bladder. In such operations it is found that as soon as the anterior wall of the bladder is opened the bladder collapses and becomes a shapeless mass, rendering it difficult to open the posterior wall and remove the prostate gland. However, by inserting a coiled retractor, shaped as shown in Figure 4 and of suitable dimensions, into the bladder through the incision in the anterior wall and then expanding it, the collapsed walls of the bladder can be distended and a clear view had of the rear wall overlying the prostate gland. In this and in other operations, a small electric lamp can be clamped to the edge of the retractor after it has been expanded to facilitate the work of the surgeon.

Many other specific uses for the device will be apparent to surgeons and it may be desirable for some purposes to provide plates of shapes different from those illustrated. It is therefore to be understood that the invention is limited only as set forth in the following claims.

I claim:

- 35 1. A retractor for insertion into an incision for the purpose of keeping the viscera from encroaching on the field of a surgical operation, comprising a pliable, non-elastic plate capable of being inserted as a whole within a body cavity and capable of being bent into any desired shape after insertion within a body cavity to form a retaining wall, said plate being sufficiently pliable to be easily bent by the hands of a surgeon but stiff enough to resist bending under pressure exerted by the tissues or organs to be retracted.
- 40 2. A retractor for insertion into an incision for the purpose of keeping the viscera from encroaching on the field of a surgical operation comprising a pliable, non-elastic plate capable of being and adapted to be bent into compact

form for insertion through a small opening into a body cavity and thereafter expanded into desired shape by the hands of a surgeon to form a retaining wall.

3. A retractor for insertion into an incision 80 for the purpose of keeping the viscera from encroaching on the field of a surgical operation comprising a pliable, non-elastic plate having edge portions of soft yielding material, said plate being capable of being inserted as a whole within a body cavity and capable of being bent into a desired shape to form a retaining wall, and being sufficiently pliable to be easily bent by the hands of a surgeon after insertion into a body cavity but stiff enough to resist bending under pressure exerted by the tissues or organs to be retracted.

4. A retractor for insertion into an incision 85 for the purpose of keeping the viscera from encroaching on the field of a surgical operation and adapted to be inserted within a body cavity 95 and shaped after insertion comprising a flat plate of pliable, non-elastic material enclosed in an envelope of rubber, said envelope being hermetically sealed.

5. A retractor for insertion into an incision for the purpose of keeping the viscera from encroaching on the field of a surgical operation comprising a flat plate of pliable, non-elastic material enclosed in a hermetically sealed envelope 105 of rubber and adapted to be inserted into and shaped within the body cavity, the outer edges of the envelope projecting beyond the edges of the plate and the plate being secured to the inner walls of the envelope to prevent relative movement therebetween.

6. A retractor for insertion into an incision for the purpose of keeping the viscera from encroaching on the field of a surgical operation and adapted to be inserted into and shaped within 115 a body cavity comprising a thin plate of lead enclosed in a hermetically sealed envelope of rubber.

7. A retractor as described in claim 1 of approximately oblong shape.

8. A retractor as described in claim 1 of elongated shape having an indentation in one long side thereof.

9. A retractor as described in claim 1 of elongated shape, wider at one end than at the other.
